Application September 27, 1934, Serial No. 745,733

15 Claims. (Cl. 40—130)

This invention relates to signs and particularly to signs and pictorial representations or figures. An object of the invention is to provide improved means by which any pictorial representation may be illuminated, with which the source of illumination may be concealed, with which the representation or figure will have a soft, pleasing, distinctive, and striking appearance under illumination, with which the pictorial representation or figure will appear to have uniform intensity of illumination in illuminated areas, which figure or representation under illumination will have the appearance of a soft glow that is visible for a very substantial distance from the sign, with which various color effects and color combinations may be produced, with which a plurality of pictorial representations may be grouped or re-grouped in a simple and practical manner, which may be used for interior or exterior purposes, and which will be relatively simple and inexpensive.

Various other objects and advantages will appear from the following description of two embodiments of the invention, and the novel features will be particularly pointed out hereinafter in connection with the appended claims.

In the accompanying drawing:

Fig. 1 is a front elevation of an improved sign unit constructed in accordance with this invention;

Fig. 2 is a side elevation of the same, partly in section;

Fig. 3 is a transverse, sectional elevation of the same, the section being taken approximately along the line 3—3, Fig. 2;

Fig. 4 is a side elevation of another sign unit, similar to that shown in Figs. 1 to 3 but illustrating a different degree of concavity in the face of the unit; and

Fig. 5 is a front elevation, on a reduced scale, of the unit shown in Figs. 1 to 3, as it would appear under illumination.

In the embodiment of the invention illustrated in Figs. 1 to 3 and 5, the improved sign unit includes a member 10 of any suitable material, which has a shallow, concave, front face 11. The member 10 may be of uniform or varying thickness, and is provided with projecting rear lugs 12 and 13 by which the unit may be supported detachably and interchangeably in any display position on a suitable supporting frame or object. The member 10, when made of metal, may advantageously be formed of cast metal, or it may be of sheet metal suitably formed by means of dies. Attached to the member 10, ad-

jacent one edge thereof, is a housing base 14 mounting a lamp socket 15.

A tubular shell 16 is suitably anchored to the base 14, so as to project therefrom in a direction approximately normal to the adjacent portion 5 of the member 10. At its outer end, this shell 16 is closed by a removable cap 17 which may telescope to some extent with the shell 16. The shell 16 is provided, along the side facing the concave face 11, with an open window 18, and this window is normally closed by a transparent element 19, such as glass, celluloid or other light conducting, sheet material. The element 19 is arcuate and slides endwise into a groove 20 provided in the inner surface of the shell 16 along 15 the window 18 and for some distance beyond the same in a direction peripherally of the shell. The cap 17 confines the transparent element 19 in the position in which it closes the open window 18. The element 19 may be clear and transparent, or tinted or colored so as to transmit either white light or colored light, as may be desired.

The inside surfaces of the shell 16 and the cap 17 are silvered, or made highly light reflecting, 25 so as to direct as much light as possible towards the window 18. An electric light bulb or lamp 21, either clear or colored, is disposed in the socket 15 and within the shell 16, and its filament 22 is approximately aligned with the 30 window 18, so that light rays leaving the filament may pass directly through the window 18 and strike the concave face 11. The inner surface of the cap 17 is preferably a portion of a sphere whose center is approximately at the concentrated portion of the filament 22, so that light rays leaving the filament and striking the cap 17 will be reflected back towards the filament in a radial direction, many of which rays will then pass directly through the window 18 along with 40 the other light rays that pass directly from the filament to the window.

The major portion of the face 11 is preferably provided with a diffusing and reflecting finish, and this finish preferably extends only 45 over an area that defines the outline of a pictorial representation or figure, such as an object or a letter, the letter F being illustrated on the accompanying drawing. The remaining portion of the face 11 is then given a black or non-light 50 reflecting finish or surface, which contrasts strongly with the light reflecting finish given the first mentioned portion of the face 11. To save material and make the unit as light as possible, the member 11 may be cut away along its 55

periphery to conform largely to the outline of the letter or other object to be pictured, except for a portion thereof which mounts the housing base 14. Thus, in Fig. 1, the portion of the face 11 below the bottom of the letter F may be painted black or other very dark color, so as to be non-light reflecting, and the exterior of the cap 17 and shell 16 are also preferably painted black or dark colored so as to be as inconspicuous and invisible as possible.

The finish given the face 11 in the area representing the object to be pictured, and which in the example illustrated is the letter "F", is mat-like or one which will reflect and somewhat diffuse the light rays striking it, and will also have the appearance of a subdued, yet satin-glow that is visible to a considerable distance in front of the face 11. As examples of such a finish, the face 11 representing the letter "F" may be coated with a bronze, aluminum, copper or gold paint, or with any other paint which produces a mat-like, similar finish. A highly polished surface is not as satisfactory as the mat-like finish.

The face 11 is also preferably provided with surface undulations, that may be in the nature of corrugations or ribs preferably running wave-like or approximately concentric about the filament or axis of the lamp 21, and such undulations are also preferably in the nature of V-shaped ribs. One side 23 of each undulation or rib is preferably made approximately radial to the filament 22, particularly the concentrated portion thereof, so that a minor portion, if any, of the light rays from the lamp 21 will strike those sides of the ribs. The other sides 24 of the ribs or undulations are preferably made as surface sections of paraboloids having a common focus or focal point located approximately at the concentrated portion of the filament 22, so that light rays leaving the filament and striking these paraboloidal surface sections will be reflected forwardly of the face 11, generally in a direction parallel to one another, but with some diffusion or slight variance.

When the letter "F" is so illuminated, largely from the light directed thereon from the filament 22, it will have the appearance of light and dark stripes progressing across the face thereof and approximately concentric with the source of light which is the lamp 21, which effect is shown in Fig. 5. The light stripes will be the sides 24 of the ribs on the face 11, which contrast with the darker or non-illuminated sides 23 of the ribs or undulations on the face 11, that because of their approximately radial relation to the filament 22 receive little or no substantial illumination.

These light and dark stripes appearing on the face of the object pictured, such as the letter "F", produce a very striking, yet pleasing effect on the eye of the observer, even if located a substantial distance in front of the face 11, and this same striking, distinctive and attractive appearance is obtained, even when there is some illumination of the sides 23 of the ribs, because the illumination of the sides 23 of the ribs will intentionally be less intense than that of the sides 24 of the ribs, and this contrast in the intensity of illumination on the sides 23 and 24 will produce a striped appearance, such as shown in Fig. 5, when the face 11 of the letter is illuminated, largely by the light from the lamp 21.

I also preferably increase the width of the sides 24 of the ribs progressively in a direction

away from the lamp 21, so that the net area of the sides 24, illuminated brightly by the lamp 21, will increase with the distance from the lamp. Because of this increase in area of illumination, with the increase in distance from the lamp 21, the appearance to an observer in front of a letter or sign unit will be one of uniformity in intensity of illumination in the light stripes, over the entire figure outline of the unit, even though the lamp is disposed entirely at one side of the letter or object being pictured. While the lamp could be disposed within the pictorial representation, it preferably is disposed slightly to one side of the representation or letter, as shown.

In Fig. 4 a somewhat similar sign unit is illustrated, and similar parts are designated by the same reference characters as in Figs. 1 to 3. In Fig. 4 the face 11 has a greater degree of curvature in the concavity than in Figs. 1 to 3, and the size of the ribs and area of the illuminated section are changed. The relationship of the sides of the ribs to the filament is the same, however, and the sides 24 are preferably sections of paraboloids, the same as in Figs. 1 to 3.

Electric wires 25 lead from each socket 15, and may be connected to the usual connection, not shown, by which each sign unit may be detachably and individually connected to a source of power, so that one may easily regroup or change the units of a sign, which makes the invention easily applicable to interchangeable signs, such as are used for advertising motion pictures, etc.

The source of light is disposed slightly in front of the face to be illuminated, and also preferably is located laterally outside of the zone or portion of the face which it is desired to illuminate and which defines the object or picture to be represented under illumination. For example, one source of light might be used for a group of pictures or objects arranged around that source, or the source of light might be disposed in the interior area of the object or representation, such as within the area encompassed by the letter "O" in which case the ribs or corrugations would preferably be approximately concentric around the source of light.

If the source of light is disposed directly in the line of sight between the observer and the illuminated portion or zone of the face which carries the reflecting finish, then the light tends to obstruct or conceal a portion of the object or pictorial representation and provides a dark area co-extensive with the lateral dimensions of the housing and lamp. While the cap 17 might be made of light transmitting properties so as to avoid the dark area, nevertheless it would interfere with the uniformity of the illuminated stripes and would tend to detract, to some extent, from the attractive appearance of the stripes of illumination across the zone defining the object or pictorial representation.

While the source of light may be disposed at the top, bottom, either side, or interior area of the object or pictorial representation, yet the rays of light from the source should strike the face having the reflecting finish at a reasonably acute angle, otherwise the appearance of light and dark stripes would be less pronounced. In referring to the face, with respect to which the light rays make an acute inclination, I am referring to the inclination to the general concave shape of the face as a whole, rather than to the

sides of the ribs against which the light rays strike.

The illustrated forms of the invention are simple embodiments thereof, and it will be understood that various devices for changing the colors of the light rays thrown on the face, or for varying the colors intermittently or in accordance with any desired cycle so as to produce moving color effects by progressive color changes in the illumination, may be adopted.

It will be obvious that various changes in the materials, proportions and other details of construction, which have been herein described and illustrated in order to explain the nature of the invention, may be made by those skilled in the art within the principle and scope of the invention, as expressed in the appended claims.

I claim:

1. A sign comprising a member having on a face thereof a plurality of approximately V-shaped ribs, concentric about a common axis, and a source of light disposed at said axis and disposed in front of, and directing light rays against said face, said face being generally concave and both sides of each rib being visible from a position well in front of said face and of said source, one side of each rib being approximately radial to said source so as to have a minimum of direct illumination from said source, the other side of each rib being clearly illuminated by said source, whereby when said face is illuminated by said source, it will have the appearance of alternate light and dark stripes thereon, concentric about said source, and when illuminated from other sources of light, both sides of said ribs will be clearly illuminated.

2. A sign comprising a member, and a source of light disposed a short distance in front of a generally concave face of said member but outside the area of said face to be illuminated and directing light rays solely against said face, said face having wave-like undulations with the wave fronts progressing from said source, and of such depths, and inclinations with respect to said light rays, that substantially one complete side of each undulation will be directly illuminated by light from said source, and the other sides of the undulations will be in shadows of the illuminated sides, said face having a diffusing, reflecting finish, whereby when said face is illuminated largely by light from said source it will have relatively light and dark stripes thereon corresponding to said undulations.

3. A sign comprising a member, a source of light disposed a short distance in front of a generally concave face of said member but outside the area of said face to be illuminated and directing light rays solely against said face, said face having wave-like undulations with the wave fronts progressing from said source, and of such depths, and inclinations with respect to said light rays, that substantially one complete side of each undulation will be directly illuminated by light from said source, and the other sides of the undulations will be in shadows of the illuminated sides, said face having a diffusing, reflecting finish, whereby when said face is illuminated largely by light from said source it will have relatively light and dark stripes thereon corresponding to said undulations, and means concealing said light from view at a position well in front of said face, and concentrating the light from said source upon said face.

4. A sign comprising a member having an undulatory face, and a source of light disposed

slightly in front of said face and laterally outside of the zone of said face to be illuminated, for directing light rays against said face at a small inclination to said face, said undulations being substantial and being approximately concentric about said source, said face having a mat-like, reflecting surface.

5. A sign comprising a member having an undulatory face, a source of light disposed slightly in front of said face and laterally outside of the zone of said face to be illuminated, for directing light rays against said face at a small inclination to said face, said undulations being substantial and being approximately concentric about said source, said face having a mat-like, reflecting surface, and a light screen for said source for concentrating the light rays from the source and directing them against said face.

6. A sign comprising a member, and an electric lamp mounted on said member adjacent an edge thereof and projecting forwardly of said member to position its filament a short distance forwardly of a face of said member, said face being concave and having thereon approximately V-shaped ribs that are approximately concentric with the filament of said lamp, one side of each rib being approximately radial to said filament and the other side of each rib being a portion of a paraboloid whose focus is at approximately said filament, whereby when said face is illuminated by light rays from said filament, said face will have the appearance of light and dark stripes thereon corresponding to the faces of said ribs.

7. A sign comprising a member having a shallow, concave face with approximately V-shaped ribs on said face and approximately concentric about a common axis, and a source of light disposed slightly in front of, and adjacent a margin of said face and approximately at said axis for directing light rays against said face, whereby when said face is illuminated by said source of light, it will appear to have light and dark stripes thereon corresponding to said ribs, said face having thereon a reflecting surface in the outline of a desired pictorial representation, and the remainder of said face being non-reflecting, whereby said outline alone will be clearly visible when illuminated by said source.

8. A sign comprising a member having a shallow, concave face with approximately V-shaped ribs on said face and approximately concentric about a common axis, and a source of light disposed slightly in front of, and adjacent a margin of the zone of said face to be illuminated and approximately at said axis for directing light rays against said face, whereby when said face is illuminated by said source of light, it will appear to have light and dark stripes thereon corresponding to said ribs, said face having thereon a mat-like, diffusing and reflecting surface in the outline of a desired pictorial representation, and the remainder of said face being non-reflecting, whereby said outline alone will be clearly visible when illuminated by said source.

9. A sign comprising a member having a shallow, concave face with wave-like undulations thereon approximately concentric to a common axis piercing said face outside of the zone of said face to be illuminated, and an electric lamp disposed with its filament approximately at said axis and slightly in front of said face, one side of each of said undulations being approximately radial to said filament, and the other sides of said undulations increasing in width somewhat pro-

- gressively in a direction from said axis toward the opposite periphery of said face, whereby when said face is illuminated by light from said filament, said face will appear to have thereon light and dark stripes of illumination approximately corresponding to said undulations, and all the light stripes will appear to have uniform intensity of illumination.
10. A sign comprising a member having a shallow, concave face with wave-like undulations thereon approximately concentric to a common axis piercing said face thereof, and an electric lamp disposed with its filament approximately at said axis and slightly in front of said face, one side of each said undulations being approximately radial to said filament, and the other sides of said undulations increasing in width somewhat progressively in a direction from said axis toward the opposite periphery of said face, whereby when said face is illuminated by light from said filament, said face will appear to have thereon light and dark stripes of illumination approximately corresponding to said undulations, and all the light stripes will appear to have uniform intensity of illumination, the sides of said undulations having a mat-like, reflecting and diffusing finish to reduce glare and provide a rich, satin-like, distinctive and attractive appearance when illuminated.
20. 11. A sign comprising a member having a shallow, concave face with a mat-like, diffusing and reflecting finish thereon and defining a zone corresponding to a desired pictorial representation, and an electric filament lamp disposed laterally outside of said zone and slightly in front of said face for directing light rays against said face, whereby said representation will be illuminated largely by indirect light from said filament.
12. A sign comprising a member having a shallow, concave face with a zone provided with a mat-like, diffusing and reflecting finish and defining by said zone a desired pictorial representation, an electric filament lamp disposed laterally outside of said zone but slightly in front of said face for directing light rays against said face, whereby said representation will be illuminated largely by indirect light from said filament, and means located laterally beyond the limits of said zone for coloring the light rays passing between said filament and said representation.
13. A sign comprising a member having a shallow, concave face with a zone carrying a mat-like, diffusing and reflecting finish thereon and defining a desired pictorial representation, and an electric filament lamp disposed laterally outside of said zone and slightly in front of said face for directing light rays against said face, whereby said representation will be illuminated largely by indirect light from said filament, said face having rib-like undulations approximately

concentric with said filament, one side of each undulation being approximately radial to said filament, and the other side of the undulations increasing somewhat progressively in width in a direction away from said filament, whereby when said face is illuminated from said filament, said zone will appear to have light and dark stripes thereacross and all of the light stripes will appear to have approximately the same intensity of illumination.

14. A sign comprising a member having a shallow, concave face, an opaque housing projecting forwardly of said face, an electric filament lamp mounted in said housing with the base of the lamp at the base of the housing, said housing having a window therein through which light from said filament may strike said face, and a transparent glass removably closing said window and having any desired color including a clear glass, so as to control the color of illumination of said face, said concave face having undulations progressing in wave-like manner from said lamp, with one side of each undulation in the shadow of the other side of that undulation, the undulations having a mat-like, light diffusing and reflecting finish in an area defining a pictorial representation, and the remainder of said face having a light absorbing and non-reflecting finish, whereby when said face is illuminated from said filament, said representation will be illuminated clearly and the remainder of said face will be relatively dark.

15. A sign comprising a member having a shallow, concave face, an opaque housing projecting forwardly of said face along an edge thereof, an electric filament lamp mounted in said housing with the base of the lamp at the base of the housing, said housing having a window therein through which light from said filament may strike said face, and a transparent glass removably closing said window and having any desired color including a clear glass, so as to control the color of illumination of said face, said concave face having upon a portion thereof a mat-like, light diffusing and reflecting finish defining a pictorial representation, and the remainder of said face having a non-reflecting finish, whereby when said face is illuminated from said filament, said representation will be illuminated clearly and the remainder of said face will be relatively dark, said face having approximately V shaped undulations approximately concentric about said filament, with one side of each of the undulations approximately radial to said filament and the other sides of said undulations increasing in width in a direction away from said housing, whereby when under illumination from said lamp, said other sides of said undulations will all appear to have an approximately uniform intensity of illumination.

CLARENCE H. MACKEY.
